(57) **CLAIM**

The ornamental design for a bullet-shaped liquor bottle as shown and described.

DESCRIPTION

FIG. 1 is a front perspective view showing my new design; FIG. 2 is rear perspective view thereof;

FIG. 3 is a front, left perspective view thereof;

FIG. 4 is a front, right perspective view thereof;

FIG. 5 is a front view thereof;

FIG. 6 is a rear view thereof;

FIG. 7 is a left-side view thereof;

FIG. 8 is a right-side view thereof;

FIG. 9 is a top plan view thereof; and,

FIG. 10 is an enlarged perspective view of the portion indicated in FIG. 4.

The stippling represents a frosted glass surface.

Although the surface is curved, straight oblique lines are used to represent the reflective nature of a portion of the bullet-shaped liquor bottle.

The broken lines represent the designation of an enlargement view and form no part of the claim.
